MULTIPLE STRAND SELVAGE

William E. Buchanan, Appleton, Wis., assignor to
Appleton Wire Works, Inc., Appleton, Wis., a
corporation of Wisconsin

Application February 4, 1939, Serial No. 254,571

3 Claims. (Cl. 139—425)

This invention relates to woven wire fabrics and more particularly to Fourdrinier wires and their selvages.

The woven wire belts used on Fourdrinier paper-making machines wear out or fail after varying periods of service and must then be replaced. A type of belt failure heretofore encountered and attributed to various causes is the cracking of the edges or selvages of the belt, such failure rendering it necessary to discard the belt even though the body portion of the belt may be in good condition.

It is an object of the present invention to provide an improved Fourdrinier wire belt which is of strong and durable construction, which will minimize the danger of edge-cracking, and which will not interfere with usual weaving practice nor materially increase the cost of manufacture.

The invention further consists in the several features hereinafter described and claimed.

In the accompanying drawing, illustrating certain embodiments of the invention,

Fig. 1 is a plan view of a portion of a Fourdrinier wire belt constructed in accordance with the invention;

Fig. 2 is an enlarged plan view of an edge portion of the belt;

Fig. 3 is a sectional view taken generally along the line 3—3 of Fig. 2, and

Fig. 4 is a view similar to Fig. 3 but showing a modified form of fabric.

The Fourdrinier wire fabric illustrated in the drawing comprises warp wires 10 and 11 interwoven with weft wires 12. The warp wires 10 and the weft wires form the main body portion 13 of the fabric, and the warp wires 11 and the weft wires form opposite selvages 14, there being a plurality or band of the warp wires 11 at each side of the fabric. The warp wires 10 are here shown to be of the usual solid round cross-section, although other cross-sectional shapes may be used. The warp wires 11 have approximately the same count as the warp wires 10, usually on the order of 60 per inch. The wire fabric will vary in fineness according to the type of paper to be produced. Each warp wire 11 comprises a plurality of strands or filaments 11', preferably more than two and twisted together, although in some instances they may be braided together.

The stranded warp wires 11 are considerably more flexible than the warp wires 10. The weft wires 12 are here indicated to be of round hollow cross-section, but other cross-sectional shapes may be used. The fabric preferably has a twill weave, but plain or other types of weaves may

be provided, as is well understood in this art. The solid warp wires 10 and the stranded warp wires 11 are woven into the fabric in the same manner, no change in loom construction or operation being necessary. It is possible, however, to use different weaves for the main body portion 13 and the selvages 14. The weft wires 12 may be crimped at their intersections with the warp wires 10 and 11, as seen in Fig. 3, or in some instances the end portions of the weft wires may have little or no crimp where they intersect the warp wires 11, as indicated in Fig. 4. The cable-forming warp wires 11 may become more or less flattened at their intersections with the weft wires, as seen in Fig. 4.

The side bands or selvages 14 of the wire fabric belt are considerably more flexible than the main body portion 13 of the belt, and each selvage has a width which is preferably relatively large compared with the thickness of the fabric. The selvage width is selected in accordance with various factors, such as the speed of the belt and severity of operating conditions. By way of example, a selvage width of one inch or more is provided in some cases, while in other instances a smaller width may be sufficient.

When the belt is in use on a Fourdrinier machine, the danger of edge-cracking is practically eliminated because of the flexibility and strength of the selvages, and the useful life of the belt will thus be extended. The paper is formed on the main body portion 13 of the fabric, and as this portion is composed of ordinary or single strand warp and weft wires, the marking of the paper is minimized. The belt portion 13 on which the paper is made has a relatively firm texture, but is still sufficiently flexible to avoid cracking.

What I claim as new and desire to secure by Letters Patent is:

1. A wire fabric for paper-making machines, comprising interwoven warp and weft wires, a plurality of the warp wires at each longitudinal edge of the fabric being arranged in a marginal band and each being formed of a plurality of strands, said bands each having a width which is relatively large compared with the thickness of the fabric to provide flexible selvages for the fabric, said selvages being more flexible than the intervening main body portion of the fabric.

2. A wire fabric for paper-making machines, comprising interwoven warp and weft wires, a plurality of the warp wires at each longitudinal edge of the fabric being arranged in a selvage-forming band and each being formed of a plurality of strands, and substantially all the warp

wires in the main body portion of the fabric each being formed of a single strand, the width of each of said bands being relatively large compared with the thickness of the fabric.

5. A wire fabric for paper-making machines, comprising interwoven warp and weft wires, the warp wires at each longitudinal edge of the fabric being arranged in a band and each being

formed of a plurality of strands, the width of each of said bands being relatively large compared with the thickness of the fabric, and substantially all the warp and weft wires in the main body portion of the fabric between said bands 5 being formed of single strands.

WILLIAM E. BUCHANAN.
